United States Patent Office

Des. 211,612
Patented July 2, 1968

211,612

FLYING BOAT

Paul P. De Asis, Yonkers, N.Y.
(24 W. 68th St., New York, N.Y. 10023)

Filed June 9, 1967, Ser. No. 7,413

Term of patent 14 years

(Cl. D71—1)

FIGURE 1 is a perspective view of a flying boat showing my new design;

FIGURE 2 is a top plan view;

FIGURE 3 is a bottom plan view;

FIGURE 4 is a side elevation; and

FIGURE 5 is a front elevation.

I claim:

The ornamental design for a flying boat, as shown and described.
